UNITED STATES PATENT OFFICE

169,246

COMBINED BATHTUB TOY AND SAFETY DEVICE

Alvin S. Eisenberg, Bronx, N. Y.

Application October 20, 1952, Serial No. 21,907

Term of patent 7 years

(Cl. D34—15)

To all whom it may concern:

Be it known that I, Alvin S. Eisenberg, a citizen of the United States of America, resident of the Bronx, city and State of New York, have invented a new, original, and ornamental Design for a Combined Bathtub Toy and Safety Device, of which the following is a specification, reference being had to the accompanying drawing, forming a part hereof.

Fig. 1 is a side elevational view of a combined bathtub toy and safety device, showing my new design; and

Fig. 2 is an end elevational view thereof.

I claim:

The ornamental design for a combined bathtub toy and safety device, substantially as shown.
ALVIN S. EISENBERG.
